UNITED STATES PATENT OFFICE.

CARL ROSENFELD, OF BERLIN, GERMANY.

ILLUSION APPARATUS.

No. 829,034.

Specification of Letters Patent.

Patented Aug. 21, 1906.

Application filed November 29, 1905. Serial No. 289,707.

To all whom it may concern:

Be it known that I, CARL ROSENFELD, director, a citizen of Germany, residing at Berlin, Germany, have invented new and useful 5 Improvements in Illusion Apparatus, of which the following is a specification.

My invention relates to illusion apparatus for the use of conjurors and others of such description that writing or other graphic representations can be caused to appear as though by some invisible agency upon the surface of what to the audience looks like an ordinary blackboard or writing-slab standing quite free from the ground. I produce 15 this mystical effect by employing a board which is capable of being turned back or otherwise reversed or has one or more flaps or like reversible panels and by providing means for concealing a performer rearward 20 of the board in such manner that when the latter is temporarily covered by some suitable means the said performer can reverse the board or a portion thereof, inscribe characters thereon, and restore the reversed 25 member or members to their initial position without being at any time visible to the spectators.

My invention is illustrated in the accompanying drawings, in which—

30 Figure 1 is a perspective view of one form of the apparatus in which a four-legged easel is employed, only that portion of the apparatus being shown which is located above the stage-floor. Fig. 2 is a detail view, drawn to an enlarged scale, showing a vertical section of the board. Fig. 3 is a vertical section of the entire apparatus, drawn to an enlarged scale. Fig. 4 is a fragmentary perspective view of a second form of apparatus in which 40 a board swings in a frame supported on a table.

Referring more particularly to the apparatus shown in Figs. 1 to 3, *a* is a blackboard consisting of a number of panels *c*, turning on 45 hinges *c'* and supported on the brackets *b'* of an easel *b*, having front legs *b²* and back legs *b³*. The joints of the panels *c* may be disguised by means of colored lines ruled across the surface of the board. The front legs *b²* 50 pass below the floor *d* of the stage, and behind them is a hole *d'* in the floor, closable by means of a hinged trap-door *d²*. The rear legs *b³* rest upon the floor *d*. The front legs *b²* present suitable guideways *b⁴*, in which 55 slide the guides *e'* of a cage or lift *e*, adapted

to be occupied by the concealed performer who is to produce the characters on the board. The cage *e* is elevated by means of a rope *f²* and winding-gear *f f'*, located below the stage. 60

In conducting the performance the conjuror removes the board *a* from the brackets *b'* and stands it against the legs *b²*, as shown by the dotted lines in Fig. 3, ostensibly for the purpose of proving to the audience that 65 there is nobody hiding behind it. He then addresses the public, offering explanatory remarks and stating that questions set to the board will be graphically replied to upon it, and so on. While the attention of the spectators is being thus distracted from the apparatus an assistant below the stage rotates the crank *f'*, thus raising a performer kneeling in the cage *e* from the position I into the position II. The conjuror then lifts the 70 board *a* and sets it upon the brackets *b'*, as shown by the full lines in Fig. 3, the assistant simultaneously winding up the cage into the position III. If the face of the board is now concealed by a suitable covering, such as a 75 second board, the performer can flap back the panels *c* into the dotted-line position, Fig. 2, write upon them, and restore them to their original position without being observed by the audience. On removal of the 80 temporary covering the writing executed by the unseen hand is naturally visible to the spectators. Naturally the performer must inscribe the characters in inverted position and reverse order, so that when the panels are 85 folded back again the letters will be displayed 90 in the proper position and order to the public.

Referring now to the modified construction of the apparatus shown in Fig. 4, the paneled board *a* is mounted to turn in the 95 frame *g* by means of pivots *g'*. *h* is a tabletop which, though apparently of but slight thickness, in point of fact is so constructed as to present a receptacle *h* behind the frame *g*, in which a performer can recline his body 100 during rotation of the board *a* or its temporary removal, (for the pretended purpose of showing that there is no deception,) being concealed from the audience with the aid of the bottom rail *g²* of the frame. When the 105 board *a* has been restored to its normal position and covered in any suitable manner, the performer rises from his recumbent position, flaps back the panels *c*, writes upon them, and closes them again, whereby on the board 110

being uncovered it appears to have been inscribed in mystical manner.

It will be obvious that instead of a stage *d*, as shown in Fig. 3, any suitable form of stand 5 or table may be employed, and any suitable devices may be provided to hold and elevate the performer. The board *a*, moreover, instead of consisting of a plurality of panels *c*, may, for example, present a single large 10 hinged panel, or the entire board may be constructed to flap back.

Having thus described my invention, what I claim as new, and desire to secure by Letters Patent of the United States, is—

15 1. An illusion apparatus, comprising a stand; a board having a swinging panel, held by the stand, there being a free space between the board and the floor; and means rearward of the board for supporting a performer; substantially as described.

20 2. An illusion apparatus, comprising a stand; a board having a plurality of swinging panels and marked with lines disguising the panel-joints, held by the stand, there being a 25 free space between the board and the floor;

and means rearward of the board for supporting a performer; substantially as described.

3. An illusion apparatus, comprising a stand; a floor, a removable board held by the stand, there being a free space between the board and the floor; means normally under the floor for holding a performer; and means for elevating the said holder to a position behind the board; substantially as described. 30

4. An illusion apparatus, comprising an easel, the front legs of which extend below the floor; a removable board held by the said easel, there being a free space between the board and the floor; a sliding lift, for holding a performer, and guided by the front easel-legs; and means for winding the lift up and down on the said front legs; substantially as 35 described. 40

In testimony whereof I have signed my name to this specification in the presence of 45 two subscribing witnesses.

CARL ROSENFELD.
